UNITED STATES PATENT OFFICE

VALERIE PROTZKY, OF NEW YORK, N. Y.

HAIR-DRESSING APPARATUS

Application filed May 16, 1932. Serial No. 611,616.

This invention relates to new and useful improvements in hairdressing apparatus, and has for its object the provision of a device, which is especially adaptable for use 5 in reconditioning the waves of marcelled or permanently waved hair, when the said hair-waves have partially disappeared or been upset by the growth of new hair.

It happens very often to ladies, who wear 10 the hair in the waved style, that in consequence of rain or foggy weather or excessive perspiration, or for some other reason, some of the hair-waves come off partially; and in such cases it is felt as a great annoyance 15 that the hair cannot be reconditioned at such places.

The object of this invention is to overcome this inconvenience by providing a hair-dressing device by means of which 20 partly disappearing hair-waves can be reconditioned within a few moments by any person, who has only the average woman's skill in handling a curling-iron. It is further the object of the invention to provide 25 such kind of a hair-dressing device, which is heated by electricity from the ordinary electric service system, which nowadays is available nearly everywhere for lighting and other purposes, so that the dangers connected 30 with the use of gas-stoves or alcohol-burners, and so on, are eliminated completely.

In the drawing, I have shown a preferred 35 embodiment of my new and improved hair-dressing device. In this drawing:

Figure 1 is a perspective view of my device in half-opened position;

Figure 2 is a view of the front-end of the device;

Figure 3 is a vertical cross-section through the middle part of the said device;

Figure 4 is a vertical section through the device at the place of the hinge-joint; while

Figure 5 is a perspective view of the 45 shield-plate, forming part of the device.

Referring more particularly to the drawing, 11 indicates the main body-portion of the hair-dressing device, and has the shape of a hollow metallic cylinder, closed at its top-end 12, and having on its circumference 50 a longitudinal groove 13. The other end of this cylindrical main-body is fastened to a stiff flat bar 14, having two lateral flanges 15 for holding the pivot 16 of a pair of tongs. With the main body-portion 11 cooperates the other body-part of this hair-dressing device, which consists of a likewise hollow metallic cylinder or rod 17, of a smaller diameter, however, so that the lower part of the said cylinder 17 fits approximately 55 into the groove 13 of the thicker main body part 11. The handle-end of this rod is likewise provided with a stiff bar-like elongation 18, which also has two lateral flanges 19, which are hinged to the aforesaid 60 pivot 16.

To the flanges 15 of the main body-portion are further pivoted or fixed two arms 20, which carry the handle 21 of the apparatus. Suitable, insulated electric resistance-wires 22 extend through the length of the two body-parts 11 and 17, which wires unite at the handle-end of the hair-dressing tongs and are passing through the handle 21, as shown in dotted lines. 75

The end-portion 12 of the larger cylindrical main part 11 has fastened to it a serrated catch-member 24, while the end-portion of the thinner hollow metallic rod 17 has been formed with a small depending and hingedly connected tongue 26, also serrated and adapted to register and engage with the catch-member 24, when the two parts 11 and 17 are locked together. The said main body 11 is further provided with 80 a groove 25. The lower side of the elongation-bar 14 of the main body-part 11 is provided with an ear 27; and a metallic bar or rod 28 with a heat insulating coating is hinged to this ear 27, whereas the front-end 85 90

of this bar or rod 28 has a small resilient tongue 29, with a button-like end, adapted to catch into the lower groove 25 on the main body-face 12.

5 A spring-wire 30 is coiled in several windings round the pivot 16, and the two ends 31, 32 of this spring-wire 30 bear against the two inner opposing sides of the metal bars 14 and 18, so as to press the two body-parts 10 11 and 17 of the hair-dressing tongs towards each other, whereas by finger pressure on the outer sides of the bars 14 and 18 the two parts 11 and 17 may be parted or opened temporarily.

15 In connection with the two body-parts 11 and 17 of the hair-dressing tongs are further used two sleeves of flannel or any other fabric, which are adapted to be slipped over the two body-parts 11 and 17, respectively.

20 As an illustration of the said sleeves, one of these with the end portions cut off is shown surrounding the member 17 in Figure 1, as indicated by 38.

There is further provided, according to 25 my invention, a thin shield-plate 33 of preferably vulcan-fibre, or any other suitable heat-insulating material, which shield-plate has the length of the main-body-part 11 and the cross-section of an arch concentric to 30 the body-part 11. This shield extends along the one side of this main-body 11, and may be fastened to it by the means of two hooked loops 34, provided at the two ends of the shield-plate and adapted to be hooked over 35 small pegs 35, provided at the front face 12 and at the opposite handle end, respectively of the main body-part 11.

From the foregoing description of the 40 different parts of my new and improved hair-waving device, the use and operation of the latter is easily understood to be as follows:

The two flannel-sleeves are dipped into a suitable lotion, as it is ordinarily used in 45 connection with hair-waving operations, and are passed then over the two body-parts 11 and 17 of the hair-dressing tongs, which are held open by finger-pressure on the two bars 14 and 18. Thereupon that particular 50 part of the hair, or lock, which is to be re-conditioned into wave-form, is placed across the groove of the thicker body-part 11, and the thinner body-part 17 is let down on it by releasing the finger-pressure on the two 55 bars 14 and 18, while the other fingers of the hand are holding the device at its handle 21. Thereafter the free swingable portion of the rod 17 is positioned in the groove with the hair or lock under it, by clamping 60 the resilient tong-member 26 into the upper groove 24 at the front-face 12 of the thicker body-part 11, and the adjacent part of the hair or lock is in the same manner clamped between the lower side of the main body- 65 part and the lower bar or rod 28, which is

clamped with the end of the tong-member 29 into the other lower groove 25 of the main body-face 12. The heat-insulating shield-plate 33 which extends along the one side of the main body 11, serves to protect the scalp of the person from being burned, when the electricity-feeding plug 23 is switched into a live-wire-connection, and in consequence of this the resistance-wires 22 are heating the two members 11 and 17 of the hair-dressing device. The lotion soaked sleeves on the tong-members are wetting the hair, so that the latter takes better to the wave-form impressed upon it by the two electrically heated tong-members 11 and 12, at the same time the said sleeves will protect the hair against being burned by too much heat.

After a few moments the plug 23 may be disengaged, the tong-members may be opened again and the hair is released, while the new wave will stay impressed on it.

It is obvious that changes may be made in the form, construction and arrangement of the several parts, as shown, within the scope of the appended claims, without departing from the spirit of the invention, and I do not therefore wish to limit myself to the construction and arrangement shown and described herein.

What I claim as new, and desire to secure by Letters Patent of the United States, is:

1. In a device of the class described, a pair of hair-dressing-tongs comprising in combination, two - cooperating tong - members adapted to be pressed against each other, means for electrically heating the said two members and means for feeding electricity to the said members, means for pressing the latter against each other, or to brace them apart from each other, and further means connected to one of the said tong-members, and adapted to secure that part of the hair to be dressed, which is adjoining the part of the hair that is being treated between the two electrically heated members.

2. In a device of the class described, a pair of hair-dressing-tongs comprising a combination, two-cooperating tong-members adapted to be pressed against each other, means for electrically heating the said two members and means for feeding electricity to the said members, means for pressing the latter against each other, or to brace them apart from each other, and two sleeves of flexible material, adapted to be slipped over the said two tong-members, so as to protect the hair to be dressed from coming into direct contact with the electrically heated tongs.

3. A pair of hair-dressing tongs, comprising in combination, an electrically heated main-body-part, having a longitudinal circumferential groove, another electrically heated body-part adapted to fit partially

into the said circumferential groove of the main-body-part, a joint connecting the two body-parts, and means for pressing the two body-parts against each other, finger-grips 5 at the two body-parts for bracing the latter apart from each other, a bar jointed at its one end to the main-body-part and below the latter, and extending along the said main-body-part, so as to clamp to it the hair 10 to be dressed, and a heat-insulating shield-plate, extending along the one side of the main-body-part and adapted to be fastened at both ends of the latter.

Signed at New York city, in the county 15 of New York, and State of New York, this 18th day of April A. D., 1932.

VALERIE PROTZKY.
